UNITED STATES PATENT OFFICE.

HARRY B. STILZ, OF PHILADELPHIA, PENNSYLVANIA.

INTERNAL-COMBUSTION ENGINE.

1,208,225.

Specification of Letters Patent. Patented Dec. 12, 1916.

Application filed May 17, 1912. Serial No. 697,894.

To all whom it may concern:

Be it known that I, HARRY B. STILZ, a citizen of the United States, residing at Philadelphia, in the county of Philadelphia and State of Pennsylvania, have invented a new and useful Internal-Combustion Engine, of which the following is a specification.

My invention relates to improvements in internal combustion engines in which combustion takes place at constant pressure, the air operated upon, being compressed in separate cylinders, up to the maximum pressure attained in the cycle and then introduced into the working cylinder, together with a supply of atomized oil, the burning of which produces a high temperature with an associated expansion in the working gases, a further expansion taking place during the time of the then remaining portion of the stroke of the piston within the working cylinder after the supply of compressed air and oil has been cut off; and the objects of my improvement are, first, to keep the air at the lowest temperature possible during compression; second, to secure a uniform mixture of air and atomized oil during admission to the working cylinder and third, to reduce heat losses during the period of expansion. I attain these objects by the mechanism illustrated in the accompanying drawings, in which—

Figure 1 is a plan view of the entire engine; Fig. 2 is a front elevation with the crank case shown in section; Fig. 3 is a sectional view through the axes of the cylinders; Fig. 4 is a part section through the expansion cylinder and head, at the admission valve, with the operating mechanism therefor in elevation; and Fig. 5 is a horizontal section of a part of the cylinder head on the line $m-m$ of Fig. 4.

The engine here shown comprises three cylinders, the piston in the power or expansion cylinder 6 driving a shaft through the usual crank and connecting rod and likewise, through special connecting rods and the rocker arm 13, operating the two-stage air compressor, having cylinders 2 and 4. Brackets on the top of cylinder 6 carry a

cam shaft, which is driven from the main shaft through two sets of bevel gears; the cams thereon operate the admission valve 9, the auxiliary exhaust valve 8 and the fuel oil pump 7. The main exhaust valve 10, through the walls of cylinder 6, is uncovered by the piston when it reaches the lower end of its stroke.

1 is a cooling chamber, through which the air must pass before entering the compressor and 3 is an intermediate receiver for the air, between the two stages of its compression. Both 1 and 3, preferably, contain pipe coils, through which is circulated a liquid having a very low temperature.

A reservoir 5, between the air compressor and the power cylinder 6, supplies reserve energy for the engine while in operation and likewise affords means for making the engine self-starting.

The auxiliary exhaust valve 8 is of the usual construction, puppet type, and is operated by a cam, through the lever shown.

The admission valve 9 is spring seated and opened by its cam operated lever. The valve 75 bonnet 11 is provided with a stuffing box and is screwed into the head of cylinder 6, which is so constructed as to form an air tight body around this valve. Co-axial with valve 9 is a duct 15, for conveying the combustible into the cylinder. The fuel-oil delivery pipe from pump 7 is connected to duct 15, at the top, by union 16. At the bottom, this duct is enlarged to receive the spiral 12, around which the fuel must circulate in its forward movement, thus establishing a violently rotating stream, which, upon escaping from the small delivery orifice 19, into the cylinder, causes it to spread out as over the surface of a cone.

The oil pump 7 is made to deliver oil during the same period that valve 9 is opened, so that the oil and the air flow into cylinder 6 simultaneously.

Compressed air from reservoir 5, enters 95 the valve body tangentially through port 14 and rotates around the valve 9, causing it to be introduced into cylinder 6 in a whirling stream, which draws within itself the mechanically atomized stream of oil dis- 10

charging from orifice 19, effecting a uniform mixture of the two fluids.

An igniter 18 extends into cylinder 6 in proximity to admission valve 9. The combustible mixture coming into contact with the igniting point of 18, sets fire to the charge, combustion continuing during the period of admission, after which the gases expand adiabatically to atmospheric pressure. The igniter is used in starting with a cold engine only. Heat retaining linings 20 and 21 are secured to the inner side of the cylinder head and top of the piston respectively. These retain sufficient heat between ignitions to ignite each subsequent charge, after the engine has been in operation a very short time. They likewise reduce the heat losses to the water jacket of the cylinder.

The efficiency of this type of engine is greatly increased by maintaining the air at a low temperature during compression. Therefore, for engines of large power, it will be advisable to circulate a refrigerating fluid through the pipe coils located in chambers 1 and 3, as well as through the jackets of cylinders 2 and 4. This refrigeration can be produced to advantage by means of the well known absorption process for liquefying ammonia, utilizing the heat within the exhaust gases from the engine for effecting this process.

Assuming that the reservoir 5 is still charged with compressed air from a previous run, and that the piston in 6 is just past dead center at the top, the operation of the engine is as follows: The oil supply to pump 7 is opened and the igniter 18 is thrown into action. The valve 17 is then thrown open and the air pressure from the reservoir 5 starts the engine. Valve 9 cuts off after a short portion of the stroke of the piston has been made and the gases confined within the cylinder expand adiabatically to the end of the stroke, when the main exhaust valve 10 is opened, relieving the charge to atmospheric pressure. The auxiliary exhaust 8 opens at the same time and remains open during a portion of the return stroke of the piston, closing in time to compress the gas then within the cylinder up to the pressure of admission, when valve 9 opens at the upper dead center. The air from 5 through 14 and the oil from 7 through 19 then enter the cylinder, forming a uniform mixture, which is ignited by 18 and the operation continued as before. While the engine is in operation, a supply of compressed air is continually being fed into reservoir 5, by the air compressor, which draws air from the atmosphere, through the cooler 1, into the low pressure cylinder 2, from which it is delivered through the intercooler 3, into the high pressure cylinder 4 and there further

compressed and delivered into the reservoir 5. The various cylinders are so proportioned that, for a given cut-off for valve 9 and with the expansion resulting from the combustion of the oil, there will be maintained the desired working pressure within the reservoir 5.

While I have illustrated a preferred form of my invention and have described this form with considerable particularity, I do not desire to be limited to the exact structural details thus illustrated and described, but intend to cover all forms and arrangements, which come within the terms employed in the definitions of my invention constituting the appended claims.

I claim—

1. A valve having a fuel nozzle centrally located therein, said nozzle having means for projecting a cone shaped film of fuel from the orifice in the end thereof, the body 86 of said valve having means therewith for discharging the air therefrom in a whirling current around said film of fuel and means for opening said valve and causing a simultaneous flow of fuel through said nozzle. 90

2. A valve having an independent passage therethrough for a combustible, an air-tight body inclosing said valve, means for causing a gaseous fluid to pass through said body and be discharged therefrom in a whirling 95 current over the seat of said valve and means for opening said valve and causing a simultaneous flow of combustible through said passage.

3. A valve having independent passages 100 therethrough for two fluids leading to a common final discharge orifice through concentric individual orifices, the inner individual orifice having means therewith for discharging the fluid therefrom in a hollow 105 cone-shaped film, means for producing a rotary motion in the fluids while passing through said common final discharge orifice and means for controlling the fluids at their respective individual discharge orifices so 110 that simultaneous flows of said fluids may be effected intermittently through said valve.

4. The combination with a cylinder and piston, an air compressor, a fuel-oil pump and an exhaust valve on said cylinder, of 115 an admission valve having an air tight body, a conduit leading tangentially into the space within said body, a fuel supply passage co-axial with said valve terminated by a small delivery orifice, a spiral overlying said passage and means for opening said valve and simultaneously operating said pump.

5. In combination with a cylinder and a piston, an air compressor, a fuel oil pump 120 and an exhaust valve on said cylinder, of 125 an air admission valve having a fuel nozzle centrally located therein with delivery direct and independent in said engine cylinder,

means for whirling the air admitted through said valve around the delivery orifice in said fuel nozzle, a conduit between said compressor and said admission valve, a conduit between said oil pump and said fuel nozzle and means for opening said admission valve

and simultaneously causing a flow of fuel through said nozzle.
